The ornamental design for a jewelry circular display stand with upstanding tower, as shown and described.

DESCRIPTION

FIG. 1 is a perspective view of a jewelry circular display stand with upstanding tower showing my new design;

FIG. 2 is a top plan view thereof;

FIG. 3 is a bottom plan view thereof; and,

FIG. 4 is a side elevational view thereof, it being understood that the display stand with upstanding tower has the same appearance from all sides.
